UNITED STATES PATENT OFFICE.

WINFIELD E. HINSDALE, OF TRENTON, NEW JERSEY.

TUNNEL KILN.

Application filed February 17, 1921. Serial No. 445,827.

To all whom it may concern:

Be it known that I, WINFIELD E. HINSDALE, a citizen of the United States of America, residing in Trenton, in the county of Mercer and State of New Jersey, have invented certain new and useful Improvements in Tunnel Kilns, of which the following is a specification.

This invention relates to kilns, ovens or furnaces of the tunnel type, wherein the articles or materials to be subjected to heat treatment are loaded on suitable cars and caused to progress continuously or intermittently through a tunnel chamber. In such kilns, it is customary to divide the structure longitudinally into three sections, of usually unequal length, the first section being that in which the material under treatment is first warmed and then pre-heated, this portion of the kiln being designated the heating or heating-up zone; the intermediate section, wherein the heat treatment is performed, will be herein referred to as the torrid zone; the final section, in which the articles or materials, after heat treatment, are gradually cooled, is designated the cooling or cooling-off zone.

Tunnel kilns have heretofore been of two types; namely, those in which direct combustion has been maintained in the tunnel chamber, so that the fire gases or products of combustion have come into direct contact with the wares or materials under treatment; and those of the muffle type, in which a thin muffle wall or partition has enclosed the tunnel chamber and separated it from the adjacent chambers or flues in which the combustion occurs, and wherein circulate the fire gases or products of combustion.

The present invention provides improved constructions of tunnel kilns, its object being to avoid certain disadvantages heretofore inherent in kilns of this type, and to improve the efficiency, economy, certainty of operation, and ease of control of such kilns. More specifically, it aims to combine the advantages of both the combustion chamber type and muffle type of tunnel kilns, and produce such a kiln which, among other uses, shall be practicable and advantageous for the burning of chinaware, porcelain and other earthenware, while avoiding the necessity of enclosing such wares in the usual saggers or protecting boxes for sealing the

ware from the action of gases that may be present in the kiln. Other important objects are to secure continuous operation of the kiln, to provide for ready inspection of the interior parts during operation, to provide for repairs without necessitating the cooling down of the kiln, so as to avoid loss of goods undergoing treatment at the time when repairs become necessary, to insure durability of the members or elements of the tunnel, by enabling them to endure changes of temperature in heating or cooling, to provide for maintaining a substantially fixed atmosphere within the torrid zone, while maintaining a continuous but slow circulation of air through the tunnel for the removal of super-heated vapor given off from the advancing wares previous to their entering into the torrid zone, and for enabling efficient control to be maintained of the temperature in the torrid zone, as well as of the duration of time during which the goods are exposed to such temperature.

To attain these advantages, the invention provides certain improved constructions, the nature of which will be developed as the description proceeds. One important feature is the provision for heating the kiln electrically, by means of successive electric furnace units which may be individually inspected and controlled from the exterior, and which, in case of need, may be individually removed and replaced without interrupting continuity of the heat treatment in the kiln.

In the accompanying drawings, a general plan is given in Fig. 1 and the other longitudinal views are divided into three equal portions, designated respectively as Figs. 2, 2^a, 2^b, etc., of which the first in each instance covers the entering portion of the kiln, in traversing which the goods are pre-heated; the second includes the torrid zone and more or less of the pre-heating zone and the initial portion of the cooling zone; and the third includes the major portion of the cooling zone, leading to the exit or emerging end of the tunnel.

Figure 1, is a plan of the tunnel kiln.

Figs. 2, 2^a and 2^b are a vertical longitudinal mid-section thereof.

Figs. 3, 3^a and 3^b are a longitudinal horizontal section, the plane of which, through the torrid zone, is indicated by the line 3^b in Fig. 14.

Figs. 4, 4^a and 4^b show the the kiln in side elevation.

Fig. 5 is an end view or elevation of the entering end.

5 Fig. 6 is a transverse section on the line 6—6 of Fig. 3.

Fig. 7 is a transverse section on the line 7—7 of Fig. 3.

10 Fig. 8 is a transverse section, in the plane of line 8—8 in Fig. 3.

Fig. 9 is a transverse section, on line 9 in Fig. 3^a.

Fig. 10 is a transverse section, on line 10 in Fig. 3^a.

15 Fig. 11 is a transverse section on the line 11—11 in Fig. 3^b.

Fig. 12 is a transverse section on the line 12—12 in Fig. 3^b.

20 Fig. 13 is an elevation of the outlet on emerging end of the kiln.

Of the foregoing views, Fig. 1 is on a greatly reduced scale. Figs. 2—4 are on a larger scale, Figs. 5 and 13 are on an intermediate scale, and Figs. 6—12 are on a 25 still larger scale.

Fig. 14 is a transverse section through the torrid zone, on the line 14—14 in Figs. 3^a and 4^a, the electric furnace at the right being shown in its operative position, and 30 that at the left removed for repairs; the view being on a larger scale than Figs. 6—12.

In the several views, the same reference 35 letters or figures designate the same or corresponding parts, throughout.

In general, the kiln is built at its ends with an outer shell of iron or steel plate, 40 suitably strengthened by ribs, and, in the central portion exposed to heat, is constructed of suitable refractory material, with openings forming dead air spaces or flues, as will be described in detail. The tunnel chamber has track rails laid through it longitudinally, on which may travel the cars or plat- 45 forms carrying the material under treatment. At the entering end and at the outlet or emerging end are doors which may be closed in a nearly air-tight manner, after the introduction and discharge of successive 50 cars.

Referring to the drawings, A designates the tunnel chamber, closed normally by a door *a* at its entering end and by a door *b* at its outlet or emerging end. The wares 55 are carried through on cars B, of any suitable construction, having, as usual, a refractory bed or hearth, which, in use, forms the bottom of the tunnel chamber. The construction shown in Fig. 14 will serve as a 60 suitable illustration of the cars, one of which is shown at B in Fig. 2^a. In both these figures, the dotted outline *x* indicates the extreme dimension of the stack of goods or 65 wares carried by the car, and very nearly filling the tunnel chamber A. The hearth

portions of the successive cars fit together so as to form a continuous union.

The tunnel kiln is divided into a succession of sections or zones, which may differ in construction, as will now be described:

70 Of these zones, C is the first warming zone; D the second warming zone; E the pre-heating zone; F the firing or torrid zone; G the first cooling zone; H the second cooling zone; and J the final cooling zone, 75 adjacent the outlet.

The first warming zone C is shown in Figs. 1—4 and the left of Fig. 6. The portion C' of the tunnel chamber A forms the inlet chamber of the tunnel. The construction of this zone is shown as having side walls 20 of iron, which may be formed of cast-iron plates or sections bolted together with their flanges preferably on the inside, the better to interfere with any air currents that may seek to flow between the stacks of wares and the chamber wall, thus breaking up such currents and forcing them towards and through the wares. The roof 21 is best constructed by crossing the chamber with ordinary T-irons and bridging the spaces between with ordinary flat arch hollow tiles. This style of roof prevents too rapid absorption of heat and gives economy of construction.

80 The second warming zone D, which encloses a section D' of the tunnel chamber A, is shown in Figs. 1—4 and the right of Fig. 6. The construction shown is the same as that of zone C, except that the walls 22 are double, being spaced preferably about 6" apart, so as to enclose between them an air space or flue 23. At the entering end of zone D, the flues 23 on opposite sides open upwardly into an air box 24, Fig. 4, forming within it a cross-over flue 25, Figs. 2 and 6, which communicates with the inlet of an exhaust fan 26, the purpose of which is to exhaust the air from the air flues 23 between the walls on opposite sides of the tunnel chamber.

85 Underlying zones C and D, is a continuous foundation 29, Fig. 2, having side walls 30, which underlie the iron panel walls 20, 22. These iron walls are at one end firmly secured to the foundation of the first panel or panels nearest the pre-heating zone E, while the remainder of the iron work of these zones is free to expand longitudinally on such supporting base. For this purpose, the flanges of the cast iron plates may be united by bolts engaging enlarged or slotted bolt holes, as is common.

90 The pre-heating zone E is shown partly in Figs. 1—4 and partly in Figs. 2^a—4^a, and in the cross-sections Figs. 7 and 8.

95 The enclosed portion of the tunnel chamber A in zone E is lettered E'. In this portion E' of the tunnel chamber, the wares are progressively pre-heated as they ap-

proach the torrid zone. This pre-heating zone E is constructed with an exterior shell or casing 32, of brick or tile masonry, suitably stiffened or reinforced by T-iron ribs or 5 other framing 33. Toward the hotter end, a refractory lining 35 is provided, which may be made up of refractory brick or tile. The roof of zone E is built of masonry in arch form, the thrust of the arch being 10 taken up by lateral members 36 of the metal framing, these being shown as T-irons tying horizontally between the extended upper-ends of the upright side frames 33. The masonry arch 37 has a lining 38 covering the 15 hotter longitudinal portion, forming a continuation of the side linings 35.

As the metal construction of zones C and D, and the masonry construction of zone E, have different ratios of expansion, and as 20 these zones are subjected to widely dissimilar temperatures, an expansion joint is formed at the junction of zones D and E. For this purpose, the masonry walls 32, 34 are extended so as to overlap the end portion 25 of the zone D, being extended inward at 40 to meet the outer wall 22, and having an inwardly extending pier 41 on each side, which meets the extended portion 22' of the inner wall of the zone D. The contact between the portions or piers 40, 41, and the respective walls of zone D, is a sliding contact, so that either section of the structure 30 may slide longitudinally with differences of temperature.

35 The piers 40 and 41 are longitudinally separated (by preferably about six feet) to form on each side an intervening chamber or air space 42; and the piers 40, 41 are extended over the top, as shown in Fig. 2, 40 forming arches 40', 41', the structure being extended upwardly at 43 and forming, over the top, an extended flue or air chamber 44, as shown in Fig. 2. These air chambers 42, 44 communicate freely with the air flues 23, 23. Extended through the remainder of 45 the zone E, on each side of the tunnel chamber E', are arranged hot air pipes 50, of suitably refractory material, such as cast iron, these pipes being superposed in upright stacks, as shown in Figs. 7 and 8. The 50 ends of these pipes are carried through the piers 41, and open freely into the chambers 42, so that the hot air may flow from them into these chambers and thence through the lateral air flues 23. The total capacity of the pipes 50 should approximately equal that of the flues 23. The pipes 50 on opposite sides of the tunnel chamber converge slightly as the carloads of wares advance, 55 being carried inside of the linings 35.

The walls 20 of the zone C and the continuing walls of the zone D, are equally spaced apart, so that the tunnel chambers C', D' are of uniform width, this width being 60 barely sufficient to safely enclose the

loads of stacks or wares carried by the car platforms or hearths, and the wares are stacked to a height to barely pass through the tunnel with safety. By reason thereof, the successive carloads of wares form, in effect, a fairly tight closure or stopper for substantially preventing the flow of air between the stacks of wares and the inner walls of the tunnel chamber. This condition continues until the zone E is reached, 70 wherein the chamber E' is abruptly widened (see Fig. 3), so that the advancing carloads of wares enter into a wider tunnel chamber, which chamber, however, is effectually shut off from the first and second warming chambers C' and D', by the presence of the cars and wares filling these chambers.

The inner refractory lining 35, enclosing the hotter part of the tunnel chamber E', is free to expand longitudinally independently of the outer wall, as it has no abutment therewith, except where the walls are widened at 51 (Fig. 3^a) adjacent to the entrance to the firing chamber F' of the torrid zone.

The firing chamber F' is partially separated from the preheating chamber E' by a contraction in the wall at 52. This contracted portion constitutes a portal to the firing chamber. The walls of this portal are located to form a tunnel opening of 90 preferably the same dimensions as the walls of the chambers C', D', affording as close an approach as is practicable to the load or stack of wares (x in Fig. 14), so as to form 95 a partial seal around the stacks of wares for obstructing the flow of air passing them. In this manner, the firing chamber is approximately shut off from the preheating chamber.

An expansion joint is formed between the 105 tunnel walls of the preheating zone E and firing zone F, being conveniently formed between the portal 52 and the expanded portion 51, as shown in Figs. 2^a, 3^a. This expansion joint is formed by one wall overlapping the other with a sliding fit admitting of expansion or contraction. In the construction shown, the portal wall is made double, an outer wall 53 being formed to embrace the end portion of the wall 51, 110 while the inner wall 54 is extended inside thereof in such manner as to form a chamber or flue 55 extending vertically in each side wall, these flues being connected by an overhead flue 56 (Fig. 2^a). The side flues 115 55 open into the ends of the radiator pipes 50 on one side, and, on the other side, open into longitudinal flues 57 (shown in dotted lines in Fig. 2^a), these flues being extended 120 through the side walls of the torrid zone F 125 of the tunnel kiln structure.

The construction of this portion of the structure is shown in cross section in Fig. 9, a transverse arched chamber 58 being formed at each side, in order to provide suf- 130

ficient length for the portal 52, while avoiding too massive masonry.

At the opposite or outgoing end of the firing chamber F', the structure is formed 5 with a substantial duplication of the portal 52, the second portal being marked 62, and having the same structure already described; that is to say, the side flues 55 and overhead flue 56 are duplicated, these flues 10 being marked 65 and 66, respectively, and the longitudinal flues 57 open into these flues 65.

The portals 52 and 62 are each of a length equalling approximately the length of one of 15 the cars B, and are formed with refractory inner walls and with suitable masonry outer walls, and overhead arch, as shown in Fig. 9. Thus, the overhead portion of each portal has an inner refractory arch 61, and an 20 outer, or upper masonry arch 64, which arches spring respectively from the inner partition walls and the outer side wall, as shown, so that they may expand and contract independently. Between these arches 25 is a dead air space 63, affording heat insulation.

The torrid zone F, with its enclosed firing chamber F', will now be described:

The outer walls 70, suitably reinforced, as 30 before, with steel framing, are erected on a succession of masonry arches 71, springing from abutments 72, Fig. 4²; and over the top of the structure is carried a masonry arch 73, Fig. 14, springing from the reinforced upper 35 portions of these walls. The inner or lining structure is constructed of the highest possible grade of refractory brick, and comprises side walls 75 made hollow to enclose the longitudinal flues 57, having arched portions 40 76 beneath, coinciding in arrangement with the outer arches 71, and roofed over by a refractory arch 77 springing between the upper portions of the side walls, which portions are laterally reinforced against the 45 outer side walls 70, as shown in Fig. 14. Between the arches 73 and 77 is a dead air space 78, forming a heat insulation. Also, between the lining wall and the outer wall, on each side, is an air chamber or cavity 50 79, forming normally a dead air space on each side of the firing chamber. These several dead air spaces serve to insulate the interior walls, so as to prevent loss of heat outwardly, thus protecting the outer walls 55 and promoting economy in the operation of the kiln.

The firing chamber F' has an average width somewhat greater than that of the narrowed portals 52 and 62, and is partially 60 subdivided at each side to form a succession of compartments 80, 80, in which, respectively, are located the firing furnaces 90, 90, which will be more specifically described later. The compartments are, in part, 65 formed by piers 81, projecting inwardly from

the side walls 75 and coinciding longitudinally with the outer arch abutments 72. Thus, the compartments coincide in number and position with the arches 71, which arches form a series of openings into the respective 70 internal compartments, through which openings the firing furnaces 90 may be introduced or removed. These arch openings in the outer wall are marked 100, and those in the inner wall 101; the inner furnace compartments are best arched over at 102, to form furnace chambers communicating with the firing chamber. When the furnaces 90 are in place, as shown at the right in Fig. 14, partitions or doors 91 close the outer 80 arches 100, and partitions or doors 92 close the inner arches 101.

The kiln, as shown in the drawings, has twelve firing furnaces 90, six on each side, but it will be understood that more or fewer 85 may be provided, the important feature being to divide the heating means into units of suitable size to admit of ready control and to distribute the sources of heat along a considerable portion of the length of the 90 tunnel, in order that the carloads of wares slowly advancing through the tunnel may be gradually raised in temperature in passing the successive furnace units. Each furnace 90 comprises a hearth 93, which, when 95 in place, is located in its respective compartment 80, partly beneath the arches 76 and 102, and between the closure or movable partition 92 and the clearway through the firing chamber F'. This hearth and the partitions or closures 91 and 92 are carried on a movable carriage or bed 94, mounted to slide laterally in a runway 95 built out over the supporting foundation 103, which forms, as 100 shown in Fig. 14, a lateral extension of the refractory bed portion 104 beneath the respective compartments 80. Anti-friction rollers 96, or any other suitable means, may be provided to facilitate the movement of 105 carriages 94 on the runways 95. For moving 110 the carriages, any suitable mechanical means may be provided, such as a screw 97 engaged by a hand-wheel 98 in a well-known manner. By this means, the several furnaces 115 may be individually removed from their normal position, as shown at the right in Fig. 14, and carried outwardly to the position shown at the left in that figure, to permit of inspection, renewal, or repairs. When any furnace is thus removed, it is 120 highly important to be able to immediately close the opening into the firing chamber, because the normal closures 91 and 92 have been taken away; for this purpose, a shut-off gate is provided for each furnace opening, these gates being preferably constructed each as a vertically sliding panel or slab 125 105, as shown in Fig. 14, which, in the normal operation, is elevated to the position shown at the right in Fig. 14, or, immedi- 130

ately after the removal of a furnace unit, is lowered to the position shown in the left of that figure. These gates thus move in the lateral dead air chambers 79, being preferably of a thickness considerably less than the width of these chambers, so that, when elevated, a suitable dead air space remains. The bottoms of the dead air space between the arches 100, 100, are closed by tiles 106 which coincide with the movable beds 94, and afford complete parallel side walls between which the beds 94 may move. The movements of the gates may be performed in any convenient manner, the means for this purpose shown comprising, for each gate, a vertical rod 107, the lower end of which is imbedded in the gate, while the portion above the gate may slide in an iron tube 108, built into the masonry, and the portion which, when the gate is lifted, is above this tube, is screwthreaded and engaged by the threaded hub of a wheel 109, having a bearing support 110 carried on the upper cross-framing 111. By means of the gates 105, any furnace units may be removed without interfering with the operation of the kiln, by merely dropping the gate to close the opening and exclude cold air from the firing chamber. Gate 105 is thus lowered before closure 92 is withdrawn from opening 100, to prevent any ingress of cold air to the firing chamber, and any loss of heat therefrom.

The firing furnaces 90 may be of any suitable or known construction, according to the fuel or source of heat which is to be used. For many reasons, however, it is preferable to use electric furnaces, instead of those heated by gas or other fuel. The principal advantage of electric furnaces is that, in their use, there is, or need be, no discharge into the firing chamber of products of combustion such as might injure the wares being fired. This avoids the necessity of protecting the wares by enclosing them in saggers, or by constructing the kiln after the manner of muffle kilns, with a lining partition of thin refractory material to separate the tunnel chamber from the lateral chambers in which the combustion or heating takes place. The use of such muffle partition requires that the heating adjacent the tunnel chamber shall be carried to a higher temperature than that required in such chamber, in order to overcome the obstruction to the flow of heat occasioned by the refractory lining wall. This is avoided by the use of electric furnaces, which can be exposed in direct communication with the firing chamber.

Several constructions of electric furnaces or heating units suitable as furnace elements in the improved tunnel kiln are known. As a suitable form of such electric furnace, the construction shown will serve as an example. In this, the hearths

93 are hollowed, and are extended longitudinally of the tunnel, the opposite ends of each hearth being entered by conducting bars or pencils 120 of carbon, preferably in graphite form, which pass through holes 121 in the hearths and through suitably lined holes 122 in the partitions 92, and are carried by carbon holders 123, which may pass through suitably lined or bushed holes 124 in the outer partitions 91. Each pair 75 of these carbons constitutes a couple, to which electric current is conducted through any suitable conducting means, such as shown diagrammatically in the form of wires at 125, in Figs. 4^a and 14. Any suitable 80 electric resistance material 99 is placed in the hollows of the hearths 93 and serves as the resistant connection between the ends of the respective carbon pencils which enter opposite ends of the hearth, this resistant 85 material being heated to incandescence by the passage of the electric current. As this material, broken or comminuted carbon is preferable.

The resistant material 99 and the carbon 90 pencils 120 need occasional renewal and this is conveniently accomplished by withdrawing the furnace units, as shown at the left in Fig. 14, in the manner already described.

The first cooling zone G extends from 95 the outlet portal 62 for a suitable distance, connecting, at its outlet end, through an expansion joint, with the second cooling zone H. The enclosed portion G' of the tunnel chamber constitutes a cooling chamber and is made wider and higher than the dimensions of the restricted opening through the portal 62, so that the inner walls 130 of this chamber, and its roof lining or arch 131 (Fig. 10) are at some 100 distance away from the carloads of wares. The outer walls 132 are of masonry supported by an external reinforcing steel framing, as before. At their entering end, these walls join the portal 62 by an overhanging slip connection to form an expansion joint in a manner which may be substantially a duplication of the joint between the wall 51 and inner and outer walls 53, 54 of the entering portal 52, already described. Fig. 10 is a section at this slip joint portion of the portal, being taken through the outer wall 133 (corresponding to 53) and inner wall 134 (corresponding to 54), between which are 105 formed the side connecting flues 65; the upper connecting flue 66 is formed between the inner arch 77 and an outer arch 136. Fig. 10.

The enclosing walls of the cooling zone G 125 are traversed by a series of air heating flues 140, which are best formed by the use, for the inner lining walls, of hollow refractory tiles 141, and similar tiles 142 to form the inner portion of the arched 130

top. The outer masonry wall 132 and outer arched masonry roof 137 are shown as directly adjoining these lining tiles.

The expansion joint 145 between the first 5 cooling zone G and the second cooling zone H is formed, as best shown in Figs. 2^b, 3^b, and 11, with an outer wall 146 and an inner or lining wall 147, which walls respectively embrace, with a slip connection, the side 10 walls 151 of the cooling zone H.

In the construction shown, the outer walls 146 form a continuation of the outer walls 132, and may be built of masonry integral therewith; the inner walls 147 are extended 15 inwardly from the tile linings 141 to the same extent as the inward projection of the portals 52 and 62. This inward projection thus forms an additional portal, designated 148. The outer and inner walls 20 enclose a connecting flue 160 on both sides and overhead, which flue serves to connect, on the one hand, the ends of all the flues 140 traversing the zone G, and, on the other hand, a flue or flues 150, formed in the 25 hollow or hollows of the wall 151 and roof portion 152 of the zone H.

The second cooling zone H has its enclosed chamber H' partially cut off from the first cooling chamber G', by the intervening portal 148 in the same manner that the first cooling chamber is cut off from the firing chamber. This zone H is best constructed of cast iron plates or sections 153, in the same manner as the heating zone D, 35 except that, for this cooling zone, it is preferable to extend the same construction over the roof, as shown in section in Fig. 12. Thus, the segmental iron plates are spaced apart, forming between them the flue 40 spaces 150, the roof plates 152 being similarly separated, and forming between them the overhead portion of this flue 150. The side walls are built on a foundation 155 of masonry, which may be continuous with the 45 foundation 155, shown in Figs. 10 and 11. The iron walls are fastened, at bottom, to this foundation, the fastening being rigid at the end portions nearest the zone G, the remainder of the side walls and top portions 50 being free to move longitudinally with changes of temperature, for which purpose longitudinally-slotted bolt-holes may be used.

The final cooling or cool zone J is a duplicate of the inlet zone C, except that it is 55 preferable to form the roof of segmental cast iron plates 162, instead of masonry or tile. The enclosed tunnel chamber J' may be an uninterrupted continuation of the chamber H', and of equal width.

At the junction 163 between the zones H and J, the outer wall 151 of the zone H is discontinued, while the inner wall is continued as the wall 164 of the zone J. The 60 space between these outer and inner walls

is left open, to constitute an inlet 161 for admitting air to the intervening space or air heating flue 150.

The outlet end of the zone J is closed by a suitable door b, which may be a duplicate 70 of the inlet door.

The masonry construction throughout has its outer wall reinforced by sectional steel framing 166 on the sides and 167 overhead, this framing serving to resist the thrust of 75 the arched masonry roofs in the manner well understood.

Having thus described the construction of the tunnel kiln, its operation may now be understood.

Following first the flow of the air through the longitudinal flues or spaces:— It is understood that the kiln, having been brought into full operation, contains a train of cars, each fully loaded with stacks of 80 wares in various stages of heating and cooling, as will be more fully described below. The air entering at 161 into the wall space or flue 150, surrounding the cooling chamber H', flows slowly through this space into the 85 connecting flue 160, thence subdivides and traverses the longitudinal heating flues 140, formed within the tile lining 141 of the cooling zone G; then, being united in the lateral flues 65 and overhead equalizing flue 66, 90 the already highly heated air is caused to flow through the two lateral flues 57 traversing the walls of the firing chamber F', then entering the lateral flues 55 and their connecting overhead flue 56 and, being again 95 subdivided, the air enters the multiple radiating pipes 50, through which it flows along the opposite sides of the zone E; from these pipes, the air is discharged into lateral flues 42 and their overhead connection 44, and 100 finally traverses the flue or air space 23 between the walls of the zone D, the air currents being finally united in the flue 25, from which they are drawn to the suction 105 fan 26, by which the current of air is maintained. During this flow of the air, it is first heated, by taking up the heat radiated from the carloads of cooling wares in the 110 cooling zones H and G, this heat being conducted to it through the lining walls of the 115 chambers H', G'; the highly heated air is then superheated while passing through the flues 57 traversing the lining of the firing chamber; the air thus superheated then, in flowing through the radiating pipes 120 50, gives out heat, which is radiated from these pipes to preheat the wares in the chamber E'; and finally the air, now partially cooled, serves, while passing through the side flues 23, to initially heat the wares 125 traversing the first heat chamber D'. Thus, the air first takes up heat from the cooling wares, and later, by a reversal of this function, gives out heat to preheat the entering wares. In the tunnel chamber E', the 130

heated air is first carried through the radiating pipes 50 (see Fig. 3^a) while these pipes are arranged close against the sides of the stacked wares; as the air loses heat, these 5 pipes recede from the sides of the cars (see Fig. 3).

It will be noted that the cooling air, which afterwards becomes the heating air, is not vitiated by products of combustion, 10 nor in any way changed in character, so that, after being discharged from the fan, its remaining heat may be utilized for heating or drying, or for any purpose for which hot or warm air is available.

15 Now, following the progress of the wares through the kiln, it is to be observed that these travel in the contrary direction to the flow of air. The successive carloads of wares are practically continuous, the wares 20 being so piled as to allow inter-spaces through which the heated air within the tunnel chamber may circulate. While other wares or materials may be treated, the present description will assume that the wares 25 are porcelain or earthenware, to be fired. The successive cars are run in through the entrance door into the warming chamber C' and this door closed. This chamber C' receives its heat entirely by means of a cer- 30 tain amount of circulation from the end of the second warming zone D, the wares slowly warming up as they pass over approximately 20 feet of track, and then entering the second heating chamber D, where they

35 first receive direct radiation from the side walls of the tunnel, where the latter are heated from the air circulating through the flues 23, on its way to the fan 26, at which time the air has given up nearly all the heat 40 it had gathered from the cooling zone and torrid zone. The iron walls of the tunnel in this section D radiate the heat directly to the wares, this effect being accompanied by convection by reason of the circulation of air in the tunnel chamber being upwards 45 along both walls to a meeting of the respective currents at the top, and thence downward through the wares to the floor of the car, and outward in both directions to the 50 walls; this rotary current being continuous and spontaneous. The flanged structure of the walls in this section D of the tunnel assists in breaking up the ascending air currents, and also provides increased radiating 55 surface. If desired, the outer iron walls may be insulated by an exterior covering of brick work or insulating material, as is common.

The ware train is kept moving continu- 60 ously or intermittently, and at a suitable rate throughout the length of the tunnel kiln. Continuous movement is preferred, and at a rate such that each car moves its own length in about one hour. As the cars

progress through the heating zone D, they 65 encounter continually hotter walls, from which there is a progressively higher heat radiation. In time, each car passes from the heating chamber D' into the final pre- 70 heating chamber E', where the tunnel chamber suddenly widens. In the progress of the cars through this chamber E', the wares receive a continually increasing heat radiation 75 from the cast iron radiating pipes 50, which, at the entering end, are somewhat separated laterally from the loads of wares, and which gradually approach these as the cars ad- 80 vance. At about halfway through this chamber, the outer brick wall of the tunnel is re- 85inforced by a fire brick lining 35 on the side walls, and 38 at the roof, as, throughout the after portion of this chamber, the heat is elevated to a degree that would be injurious to common brick. Throughout this chamber, the same convective lateral circulation 90 of air within the tunnel chamber and through the wares takes place, except that, as the heat is constantly becoming more intense, this circulation is probably more rapid and effective. In the final portion of this 95 chamber, the radiating pipes are brought as close to the sides of the loads of wares as possible, in order to make this lateral circulation the most effective.

In this section E of the tunnel is intro- 95 duced an important improvement in such kilns:

The ware entering the kiln is at a stage of process called chalk white; that is, the clay is predried to a point where there is no apparent moisture present but molecular moisture remains, and, as the car progresses in the kiln, is liberated from the ware and is present as superheated vapor in the circu- 100 lating air surrounding the ware train. It is 105 necessary to remove this moisture; and for that purpose and also for the purpose of replenishing oxygen within the kiln, advan- 110 tage is taken of a certain amount of air leakage at the doors at either end, also air leakage into the tunnel at a number of spy holes and a leakage in the side walls about the fire hearths in the torrid zone. A stack 115 170 is built over the tunnel at approximately one-third of the length of the pre- 120 heating chamber E' forward of the entrance to the torrid zone, and being connected directly with the interior of said chamber, creates an updraft which drawing on the tun- 125 nel interior produces a slow current from both ends, the current from the entrance end carrying with it the molecular moisture vapor which, being always lighter than the normal air of the tunnel, readily finds its outlet to the stack, while the current from the exit end, aiding primarily in cooling the ware on its way through the tunnel to the stack, takes up the peak heat of the torrid

zone and entering the preheating chamber largely assists in completing the preheating process.

The ware train having passed the vent stack, now without moisture continues to the portal 52 of the torrid zone chamber. This portal, like the entrance to all other chambers, is substantially continuously closed by the ware train structure and contents. This 10 closing of portals checks all circulation, except for the slow movement of air to the preheating vent stack, and the rotary circulation previously noted and which is alike in all chambers (except that in the colling 15 zone it is reversed). While within the portal the carload of wares is substantially cut off from external sources of heat for a suitable time (preferably at least one hour), so that during this time any irregularity in 20 preheating of different portions of the wares is corrected by mutual radiation and convection, thus accomplishing an equalization of the preheating throughout the load of wares.

25 While in the torrid zone or firing chamber, the ware train is between two rows of direct fire from the furnaces 90, 90. The advancing ware just entering from the preheating chamber receives the direct heat 30 from the first pair of furnaces, and thereby is gradually elevated in temperature. Passing, next, the second pair of furnaces, it is farther elevated in temperature, attaining its maximum temperature at the fourth pair 35 and maintaining this temperature past the fifth and sixth units (this action being modified in the case of a greater or lesser number of such units). During the latter part of 40 their passage through the firing chamber, the wares are at incandescence, and, while passing through the outlet portal 62, the lining of which is incandescent, this incandescence is maintained, thus giving the wares a steady "soak," without fire, for that 45 period. This static heat treatment in the outlet portal repeats in a manner the heat equalization occurring in the inlet portal, so that if the wares are unequally incandescent, or at unequal temperatures, this 50 inequality is corrected by mutual radiation and by convection.

On leaving this outlet portal, the wares 55 enter the first cooling chamber G', in which the heat radiated from the wares is taken up slowly by the hollow tile wall and arch construction, and transmitted to the air circulating through the flues formed in these hollow tiles. As the ware train advances, the 60 wares continue to give up heat thus to the absorbent walls, the convective action now occurring by circulating up through the wares to the roof and down the sides of the tunnel to the floor of the car, thence returning to the roof; and, because of this 65 circulation and of the absence of any perceptible

draft through the tunnel, the wares cool gradually and equally, thus avoiding danger of breakage through unequal contraction. This action proceeds progressively during the slow advance of the carloads of wares 70 through the first cooling chamber G'. On passing out from this chamber, the wares substantially fill the outlet portal 148 thereof, thereby obstructing and substantially preventing any material longitudinal circulation of air through the tunnel chamber. 75

On entering the second cooling chamber H', the wares continue to give out heat which, conducted through the inner iron walls of this chamber, is taken up by the 80 cool air circulating through the hollow space or flue 150 in the side walls and roof. This construction provides for ready and rapid absorption of heat from the walls so that, when the latter have reached the end of this 85 section at 163 and enter the single wall construction of the final cool section J, the wares will have cooled to such an extent that, on their final passage through this section for a distance of about 20 feet (taking 90 some 3 hours), the wares undergo a tempering process under cover which puts them in condition for safe exit to the open air. Finally, as each car reaches the exit opening, the end door b is opened and the car 95 run out and the door then again tightly closed.

The total length of the tunnel kiln and the proportionate lengths of the successive heating zones of the torrid zone and of the 100 cooling zones are matters which may be approximately arrived at by computation based upon past experience with tunnel kilns of other types, but which may be finally determined as to the best proportions only after a sufficient degree of experience in the use of tunnel kilns of this improved type; and these proportions will be subject to variance according to the requirements of different kinds of wares or different heat treatments for which the kiln is to be used. 105

An important feature of the improved construction herein set forth is the provision of means for protecting the tunnel structure against the injurious or destructive effects of expansion and contraction. To provide for expansion and contraction in longitudinal direction, the kiln is divided longitudinally into sections which, in their 115 nature, are subject to varying temperatures in use, and, consequently, to varying degrees of expansion and contraction while heating up and cooling down before and after a period of practical service. The construction of expansion joints at the meeting places of these successive sections, as already described, makes adequate provision for allowing for the effects of expansion in this direction. 120

Lateral and vertical expansion is also provided for; but, as there is little, if any, lateral movement of the walls or of the base foundations, the roof arches are the only members to be considered; and, since the thrust of the arches is always taken up against the steel reinforcement, it follows that the only movement due to expansion would be a bowing upwardly of the crowns of the successive arches. It is, therefore, seen that the tunnel structure is free to expand from its built dimensions to a new heated dimension, and, when cooled at any time, its dimensions are diminished from its expanded position, this being taken up in the expansion joints and by, in some cases, the opening of joints in the side walls, while the arch crown will lower somewhat in cooling; all parts of the structure, however, returning to their fixed expanded position when again heated.

In order to provide for ready inspection of the fire hearths and of the wares in their progress through the firing chamber, suitable peep holes are provided in the sides and at the ends of this chamber. The lateral peep holes are best formed at 171, Figs. 2^a and 4^a, that is, through the stopper walls or doors 91, 92, pertaining to the individual furnaces. End peep holes 172 are formed on opposite sides and at opposite ends of the firing chamber (see Fig. 3^a), these peep holes passing through end walls 173 forming the inner masonry members of the portals 52 and 62 respectively. The arched recess 58, already referred to in describing the portal 52, and corresponding recesses 68 pertaining to portal 62, afford compartments opening externally which may be entered to make use of these spy holes. The provision of these holes makes possible a ready inspection of the fire hearths from either end, and also enables a vision of the passing cars. As the spy holes at either end will sweep a field of more than one-half the length of the fire chamber, it follows that the cars and wares in the firing chamber are always under visual inspection.

The improved tunnel kiln herein set forth is designed and ideally adapted to maintain an intense heat in the torrid zone and a practically quiescent firing chamber from which no material loss of heat occurs; with the result that, when, in the original firing up of the kiln, the heat once reaches its peak, it may be maintained over long periods at relatively low cost of operation. In the firing chamber, the longitudinal flow of heated air, due to minute leakage through the end doors, furnace joints, peep holes and other interstices, is so slow that such longitudinal flow becomes negligible so far as affects the practical quiescence of the atmosphere within this chamber.

By referring to this atmosphere as quiescent, I do not negative the normal rotative circulation of air in transverse planes, by which the uniformity of heating and the equal incandescence of the wares throughout the stack thereof, is assured. Nor do I ignore the extremely slow flow of air, in volume equal to the aggregate in-leakage, toward the stack 170, already described.

It will be evident from the foregoing description, that the invention may be modified in construction, proportions and details in many ways, according to local conditions and the specific uses to which the tunnel kiln is to be applied. I desire it understood that all such modifications which are within the scope of the appended claims are to be deemed within my invention.

What I claim is:

1. A tunnel kiln having a continuous tunnel chamber and successive cars traveling therethrough, the kiln comprising a heating zone, a torrid zone, and a cooling zone, having end doors, and the inlet and outlet portions of the tunnel chamber formed of minimum cross-section closely approximating that of the carloads of stacked wares under treatment, whereby to substantially close the end portions of the tunnel and prevent inflow of air toward the torrid zone, and the firing chamber at the torrid zone of greater cross-section, and having a dead air insulation surrounding the tunnel chamber, whereby when once heated to operative incandescence the kiln conserves heat and permits economic operation, and means for absorbing heat radiated from the wares traversing the cooling zone, conveying such heat past the firing chamber, and radiating it in the heating zone to preheat the wares therein.

2. A tunnel kiln according to claim 1, the firing chamber being heated by multiple electric furnaces under independent control, whereby the advantages of electric heating are rendered available under economic conditions.

3. A tunnel kiln having a tunnel chamber for the passage of cars traveling therethrough, comprising a heating zone, a torrid zone, and a cooling zone, the torrid zone formed as a firing chamber with a double arched roof and dead air insulation in such roof and in its side walls, and expansion joints of overlapping refractory masonry at the junction of the torrid zone and the heating and cooling zones.

4. A tunnel kiln formed with an expansion-joint where the torrid zone joins a portion of the kiln subject to less extreme temperature changes, and having a transverse chamber coinciding with such expansion joint.

5. A tunnel kiln structure comprising a

- torrid zone forming the firing chamber, and preceding and succeeding zones which are normally subjected to lower temperatures, such zones partially separated by portals 5 on both sides of the firing chamber adapted to closely enclose the carloads of wares to substantially cut off circulation of gases between such zones, and of a length such as to enclose a carload mass of wares, the 10 tunnel structure formed between the torrid zone and the adjacent zones, with refractory masonry portions forming an expansion joint to enable the respective sections of the structure to expand or contract independently.
- 15 6. A tunnel kiln structure according to claim 5, having longitudinal flues through the masonry walls, and having transverse chambers at the expansion joints connecting the flues on opposite sides of such joints.
- 20 7. A tunnel kiln structure divided transversely into longitudinal sections which are subject to diverse temperatures, such sections meeting with a double sliding joint, and a lateral flue chamber at such joint, 25 whereby the movements due to temperature changes are taken up in such lateral chamber.
- 25 8. A tunnel kiln the torrid zone of which joins the preceding and succeeding portions of the kiln with expansion joints of refractory masonry, having transverse chambers at the expansion joints, and longitudinal flues in the masonry walls, the flues 30 on opposite sides of such joints communicating through said chambers.
- 35 9. A tunnel kiln the torrid zone of which is formed with a firing chamber partially 40 separated from the preceding and succeeding zone by portals adapted to closely enclose the carloads of wares, such portals of a length such as to enclose a carload mass of wares and hold them in thermostatic 45 condition for a time sufficient to effect equalization of temperatures.
- 40 10. A tunnel kiln having a heating zone and torrid zone, the tunnel chamber between such zones being contracted to form 50 a portal closely approximating the cross-section of the carloads of wares, so as to substantially cut off circulation between such zones, and such portal of a length sufficient to enclose the moving carload of wares and 55 hold them in thermostatic condition for such time as to effect equalization of their temperatures.
- 55 11. A tunnel kiln having a torrid zone and a cooling zone, the tunnel chamber between such zones being contracted to form 60 a portal closely approximating the cross-section of the carloads of wares, so as to substantially cut off circulation between such zones, and such portal of a length sufficient to enclose the moving carload 65

of wares and hold them in thermo-static condition for such time as to effect equalization of their temperatures.

12. A tunnel kiln having a heating zone, a torrid zone and a cooling zone, the torrid zone formed as a firing chamber of greater cross-section than the traveling carloads of wares, and such chamber formed with lateral compartments of greater width, independent portable heating units in such 70 compartments on opposite sides of the carloads, lateral openings to permit the removal of any of such heating units, and means for closing such openings.

13. A tunnel kiln the torrid zone of which is provided on opposite sides of the tunnel chamber with successive heating units, and means for permitting the removal of any one unit independently of the others, and means for closing communication with the chamber upon the removal of such unit.

14. A tunnel kiln the torrid zone of which is formed on opposite sides with successive furnace compartments, and independent furnace units in such compartments.

15. A tunnel kiln the torrid zone of which is formed on opposite sides with successive furnace compartments, and independent furnace units in such compartments, such units being individually removable.

16. A tunnel kiln the torrid zone of which is formed on opposite sides with successive furnace compartments, and independent furnace units in such compartments, such units being individually removable, and means for closing off any compartment upon the removal of its furnace 100 unit.

17. A tunnel kiln the torrid zone of which is formed on opposite sides with successive furnace compartments, and independent furnace units in such compartments, such units being individually removable, carriages for the individual furnace units, and closures on said carriages for the openings through which the units are removable.

18. A tunnel kiln according to claim 17, with independent closing means for shutting off any compartment when the furnace is removed.

19. A tunnel kiln having at its torrid zone on opposite sides a series of successive independent electric furnaces, with means for controlling them individually, and means whereby said furnaces may be independently removed and replaced.

20. A tunnel kiln having at its torrid zone on opposite sides a plurality of electric furnace units, and means for controlling the individual units independently, with openings through which such units are 130

independently removable, and means for closing such openings.

21. A tunnel kiln having at its torrid zone a plurality of electric furnace units, each unit independently removable, the kiln having openings for permitting their removal and movable doors for closing such openings.

22. A tunnel kiln the chamber of which 10 at its torrid zone is formed with successive compartments, exterior openings communicating with such compartments, doors for closing such openings, and electric furnace units movable through such openings into 15 such compartments.

23. A tunnel kiln having at its torrid zone a plurality of electric furnace units, each unit independently removable, and carriages for such furnace units.

24. A tunnel kiln having at its torrid zone a plurality of electric furnace units, each unit independently removable, and carriages for such furnace units, the kiln having openings for passing such carriages and units, 23 and doors for closing such openings.

25. A tunnel kiln having at its torrid zone a plurality of independently removable electric furnace units, each such unit comprising a hearth, carbon pencils leading to such hearth, and resistant material on said hearth bridging said pencils.

26. A kiln according to claim 22, having lateral runways through said openings, and carriages for the furnace units traveling in 33 such runways.

27. A tunnel kiln having at its torrid zone a plurality of electric furnace units, each unit independently removable, and carriages for such furnace units, the kiln having openings for passing such carriages and units, 40 and doors for closing such openings carried on such carriages to close them when the units are in place, and separate means for closing such openings when the units are 45 removed.

28. A tunnel kiln comprising a heating zone a torrid zone and a cooling zone, means for transmitting heat radiated by the cooling wares to preheat the wares in the heating zone with electric furnaces for heating 50 the torrid zone, whereby discharge of burning gases into the kiln is avoided, the kiln having suction means for drawing air from the tunnel chamber at a point in the heating zone, the rate of suction graduated to remove vapor being evaporated from the pre-heated wares without material indraft of hot gases into the heating zone from the torrid zone.

29. A tunnel kiln comprising a heating 60 zone, a torrid zone and a cooling zone, with electric furnaces for heating the torrid zone, whereby discharge of burning gases into the kiln is avoided, the kiln having suction means for drawing air from the tunnel

chamber at a point closely preceding the torrid zone, its rate of suction graduated to be only sufficient to remove inleaking air, but not sufficient to impair the normal convection effect in the torrid zone chamber. 70

30. A tunnel kiln comprising a heating zone, a torrid zone and a cooling zone, the torrid zone and heating zone partially separated by a portal adapted to closely enclose the carloads of wares to substantially cut off circulation of gases between such zones, and of a length such as to enclose a carload mass of wares, with electric furnaces for heating the torrid zone, whereby discharge of burning gases into the kiln is avoided, the kiln having suction means for drawing air from the tunnel chamber in the heating zone, its rate of suction graduated to be only sufficient to remove inleaking air, but not sufficient to prevent the spontaneous lateral circulation of air within the tunnel chamber. 75

31. A tunnel kiln comprising a heating zone, a torrid zone and a cooling zone, the torrid zone and heating zone partially separated by a portal adapted to closely enclose the carloads of wares to substantially cut off circulation of gases between such zones, and of a length such as to enclose a carload mass of wares, with electric furnaces for 80 heating the torrid zone, whereby discharge of burning gases into the kiln is avoided, the kiln having suction means for drawing air from the heating zone of the tunnel chamber at a point closely preceding the torrid zone, graduated to operate at a rate only sufficient to remove inleaking air, whereby such air circulates slowly through the cooling chamber, the torrid chamber, and into the heating chamber. 100

32. A tunnel kiln having a heating zone, a torrid zone and a cooling zone with electric furnaces for heating the torrid zone without discharge of combustion gases thereinto, the tunnel chambers contracted 110 at the junction of the torrid zone with the heating and cooling zones to form portals closely approximating the cross-section of the carloads of wares, so as to substantially cut off circulation between such zones, and such portals of a length sufficient to enclose the moving wares and hold them in thermodynamic condition for such time as to effect equalization of their temperatures, and suction means for drawing air from the heating zone at a rate sufficient only to remove inleaking air, whereby to cause a slow circulation of air longitudinally of the torrid zone. 115

33. A tunnel kiln having a preliminary 120 heating zone, an intermediate torrid zone, and a final cooling zone, the torrid zone having insulating walls to retain the heat, and air flues therein insulated from the exterior walls, and the preheating zone and cooling zone 125 130

- having lining walls insulated from the exterior walls, and air flues in their lining walls, and means for circulating air first through the flues of the cooling zone to absorb heat from the cooling wares, then through said flues passing the torrid zone, and finally through the flues of the heating zone to impart to the wares approaching the torrid zone the heat taken up by the air.
34. A tunnel kiln according to claim 33, the flues passing the torrid zone having no communication with the heating means.
35. A tunnel kiln according to claim 33, the flues passing the torrid zone being formed in the lining walls thereof remote from the source of heat.
36. A tunnel kiln according to claim 33, the flues in the heating zone being formed in the side lining walls of the kiln.
37. A tunnel kiln according to claim 33, the means for circulating the air being a suction fan applied at the delivery from said flues in the heating zone.
38. A tunnel kiln according to claim 33, the flues passing the torrid zone having no communication with the firing chamber.
39. A tunnel kiln the firing chamber of which has contracted portals at opposite ends, with lateral recesses in such portals, and peep holes opening from such recesses into the ends of the chamber.
40. The torrid zone of a tunnel kiln having its sides formed with successive abutments and arches thereover, side walls above said arches, an arched roof, and lining walls similarly arched to form successive compartments at the sides of the firing chamber, and removable closures for the lateral arched openings.
41. A tunnel kiln having lateral openings into its firing chamber, movable doors for normally closing said openings, and extra closures movable into said openings before the removal of said doors, whereby to prevent ingress of cold air.
42. A tunnel kiln having lateral openings into its firing chamber, laterally removable furnace units having portions normally closing such openings, and extra closures movable into said openings before the removal of said normal closures.
43. A tunnel kiln having lateral openings into its firing chamber, laterally removable furnace units having portions normally closing such openings, a movable bed carrying each such furnace unit and closure, and an extra closure for each opening, movable thereinto before the removal of said normal closure.
44. A tunnel kiln having its torrid zone formed with inner and outer side walls, with dead air spaces between them, and having lateral openings in its side walls, furnace units accessible through said openings, and spaced closures for said openings having spaces between them forming continuations of said dead air spaces in the side walls.

In witness whereof, I have hereunto signed my name.

WINFIELD E. HINSDALE.
